(57) **CLAIM**

The ornamental design for an insulated tumbler, as shown and described.

DESCRIPTION

FIG. 1 is a front, right, top perspective view of an insulated tumbler, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is another front, right, top perspective view thereof, shown with the locking mechanism of the lid in an alternate configuration;

FIG. 10 another front, right, top perspective view thereof, shown with the closure of the lid in an open configuration; and,

FIG. 11 is an exploded front, right, top perspective view of the insulated tumbler of FIG. 1.

The dashed broken lines in the figures illustrate portions of the insulated tumbler that form no part of the claimed design.

1 Claim, 11 Drawing Sheets
